(57) **ABSTRACT**

Pliers for use in a narrow space, including: a pair of neck sections which are pivotally connected with each other by a shaft rod and can be opened and closed; a pair of jaw sections located on one end of the neck sections in the same direction to define a pliers mouth; and two grips disposed at the other ends of the neck sections for a user's hands to hold and control the jaw sections to open or close. At least one of the grips is pivotally connected with a corresponding neck section, whereby the grip can be rotated about an axis parallel to a longitudinal direction of the pliers into different operation aspects and adapted to different operation sites.

5 Claims, 5 Drawing Sheets

FIG. 1
PRIOR ART

FIG. 2
PRIOR ART

FIG. 5

FIG. 6

FIG. 7

FIG. 8

FIG. 9

- a) a shaft hole in one of the second hand grip and second neck section; and,
  - b) a pivot shaft extending from the other of the second neck section and second hand grip and pivotally engaging the shaft hole.
3. The pliers of claim 2 wherein the pivot shaft extends from the second neck section in a direction opposite from the associated jaw section.
4. The pliers of claim 1 further comprising a detent mechanism acting between the second neck section and the second hand grip to releasably hold the second hand grip in the first and second positions.

5. The pliers of claim 4 wherein the detent mechanism comprises:

- a) two location indentations on one of the second hand grip and second neck section; and,
- b) a ball member located in the other of the second neck section and second hand grip, the ball member being biased into engagement with one of the locating indentations.
